UNITED STATES PATENT OFFICE.

STUART W. CRAMER, OF CHARLOTTE, NORTH CAROLINA.

HUMIDIFYING AND AIR-MOISTENING APPARATUS.

No. 873,924.

Specification of Letters Patent.

Patented Dec. 17, 1907.

Application filed August 2, 1907. Serial No. 386,775.

To all whom it may concern:

Be it known that I, STUART W. CRAMER, a citizen of the United States, residing at Charlotte, in the county of Mecklenburg and State 5 of North Carolina, have invented certain new and useful Improvements in Humidifying and Air-Moistening Apparatus; and I do hereby declare the following to be a full, clear, and exact description of the invention, 10 such as will enable others skilled in the art to which it appertains to make and use the same.

My invention relates to humidifiers and air moistening apparatus, has for its object increasing or diminishing the amount of moisture without varying the amount of air handled or the fineness of the spray, and consequently without varying the air cleansing effect, and the invention consists in certain improvements which will be fully disclosed in 20 the following specification and claims.

It is well known that for certain situations it is necessary to discharge less spray than is desirable at other places, and also that reducing the spray by adjusting the spray-head or nozzle, lessens the amount of air handled, in the induced draft type of single casing humidifiers. Now as the air cleansing effect is directly proportionable to the 30 amount of air handled, and the desirability of air cleansing is one of the chief reasons for the adoption of the outer and inner casing or wall types with their large air capacity positively handled, it is evident that any reduction of air capacity must be viewed with extreme disfavor and that any form of construction that will obviate such a fault is highly desirable.

In my improved form of construction, I 40 use a fixed spray-head or nozzle that always delivers a continuous and uniform spray and requires no adjustment whatever. The amount of spray issuing from the discharge end of the inner casing or wall is regulated 45 entirely by the size or area of the opening between the lower end of the inner casing or wall and a conical deflector which is adjustably secured, as may be desired. In other words, the spray is simply throttled by partially closing the discharge opening, by moving the deflector towards the bottom or discharge end of the inner or spray-chamber; and conversely, by lowering the deflector, full discharge opening for the spray is secured and consequently maximum capacity. 55 In neither case however, is there any change

in the amount of air handled. The deflector can be moved up until only enough spray is mixed with the air to secure practically colorless saturated air; or the deflector can be 60 let down until enough spray is admitted to the air current to surcharge it so highly as to give the appearance of steam vapor as it issues from the apparatus.

A further purpose is to secure a maximum 65 of humidifying effect and immunity from "wetting down" the floor. Many schemes have been devised to prevent "wetting down", but curiously enough have been along the line of reduction of capacity rather 70 than the contrary. The usual construction, is to turn the lower edge of the casing up to form a trough to carry off the surplus water and to prevent the air getting at or coming 75 in contact with it.

Heretofore the trouble has been that the current of air has been allowed to blow the coarser particles and drops of water outward which "wet down" the floor under each apparatus; and so the practice of catching the 80 coarser particles and drops of water in a trough attached to the lower end of the casing, did stop the "wetting down." But, I propose doing the very opposite, thereby 85 accomplishing the same result and yet utilizing the humidifying effect of the very considerable quantity of water which is otherwise lost. I plan to divert a part of the air current and let it blow inward and across the drip from the lower edge of the inner casing or wall. It will be thus seen that not 90 only is there enough water to saturate that part of the air, but also the direction of the current is such as to always keep the coarse particles of water blown inward and toward 95 the center rather than outward. This effect is further secured by the direction given to the remaining current of air between the outer and inner casings or walls, which is such as to beat down and inward any stray 100 particles that may be emerging with the spray which is drawn out by the outgoing air current. The diverting of a portion of the air current is accomplished by an annular receptacle or trough of novel shape supported 105 from the pan below by standards attached to the outer casing; this deflecting trough being so placed as to catch a part of the air current on the outside and the drip from the inner casing or wall on the inside; the bulk of the 110 drip is blown inward with such force as to convert a considerable quantity into spray,

and any surplus overflows through apertures down the supporting standards to the pan.

In the accompanying drawings, which form part of this specification:—Figure 1 represents a vertical section partly in elevation of a device embodying my invention, and Fig. 2 a plan view on line 2, 2, Fig. 1.

Reference being had to the drawings and the designating characters thereon, the numeral 1 indicates the outer casing or wall provided with an outwardly flaring deflecting skirt 2. 3 the inner casing or wall, both of which walls are preferably cylindrical and the latter arranged concentrically in the former and supported thereon by suitable braces 4, or in any preferred manner, and the two walls 1 and 3, form an annular air chamber or passage 5 between them.

6 indicates an electric motor, to whose shaft 7 a fan or propeller 8 is secured for supplying air to the device. The motor is secured to a frame 9 resting upon the upper end of the casing 1 and is properly secured thereto.

10 indicates a spray chamber within the wall 3 and is supplied with atomized spray from a spray-head 11, which spray strikes a fixed spreader 12 on a bar 13 and diffuses the spray in the spray-chamber in a highly attenuated or cloud like condition. At the lower or discharge end of the spray-chamber is a conical deflector 14 adjustably supported on the wall 3, by hooks 15 secured to said wall and hangers 16 secured to the deflector, and each hanger is provided with a plurality of holes 17 which engage the hooks 15, and provide for vertical adjustment of the deflector to throttle the spray in its passage from the chamber 10, to suit the conditions required and regulate the amount of spray which is commingled with the air flowing through the annular passage 5.

At the lower end of the wall 3 is an outwardly and downwardly extending deflecting flange 18 against which air in its passage through the chamber or passage 5 impinges and the major portion thereof is directed outward toward the skirt 2 on the outer wall or casing 1.

19 is an annular trough or receptacle below and separate from the wall 3, and arranged to catch the water which accumulates on and flows down the wall 3 and its flange 18. The trough is preferably provided with an angular bottom 20 and an inwardly inclined outer wall 21, which extends above the lower end of the flange 18, and deflects air inward across the receptacle and carries the heavier particles of water toward the center of the spray-chamber, where they impinge against the conical deflector 14 and are again comminuted by contact therewith. The wall 21 is provided with out-

lets 22 through which excess water is discharged and flows down the hangers or braces 23 on which the receptacle is supported, into the drip pan 24 which collects the surplus water.

The deflector 14 is provided with a flange 70 at its periphery for arresting and detaining heavy particles of water, and with openings 26 for allowing it to escape into the drip pan 24.

The drip pan 24 is provided with an upwardly inclined flange 27, which extends beyond the skirt 2 on the outer casing or wall 1, and the air flowing down the passage 5 is diverted by the inner surface of the skirt 2, toward the center of the device and by contact with the spray emerging from the spray-chamber beats back the heavy particles of water toward the center of the drip pan 24, where they gravitate into the pan and reduce the "wetting down" of the floor to a minimum. At the same time the air passing out directly is discharged radially, draws the spray from the spray-chamber and is mixed therewith before it issues into the surrounding atmosphere. Water is conducted from the drip pan 24 through an opening 28. It will thus be observed that the flow of the air is constant and unvaried, and the supply of spray is also constant, but its discharge is regulated to produce the results desired, and that the constant tendency of the construction is to force or drive the particles of water inward and prevent their escape in such condition that they can produce "wetting down".

It is obvious that changes in details of construction may be made without departing from the spirit of my invention.

Having thus fully described my invention, what I claim is

1. In a humidifier, a casing, means for producing a current of air through the casing, a spray-chamber within said casing, means for supplying spray to the spray-chamber, an adjustable deflector at one end of the spray-chamber, and means for collecting surplus water at the discharge end of the casing.

2. In a humidifier, a casing, means for supplying air to the casing, a spray-chamber within said casing, means for supplying spray to the spray-chamber, a conical deflector at the outlet end of the spray-chamber, means for varying the area of the opening between the spray-chamber and the deflector, and means for collecting surplus water at the discharge end of the casing.

3. In a humidifier, an outer casing, and an inner wall forming a spray-chamber, an annular passage between said casing and said wall, means for supplying air to said annular passage, means for supplying spray to the spray-chamber, a conical deflector at the discharge end of the spray-chamber provided with means for regulating the amount of

spray delivered to the air issuing from said annular passage, and means for collecting surplus water.

4. In a humidifier, an outer and an inner wall, an annular passage between said walls, a spray-chamber within the inner wall, means for supplying air to said annular passage, means for supplying spray to the spray-chamber, means for variably mixing the spray and the air, means for directing the mixed spray and air radially from said walls, and means for collecting surplus water.

5. In a humidifier, an outer and an inner wall, a passage between said walls, a spray-chamber within the inner wall, means for supplying air to the passage between said walls, means for supplying spray to the spray-chamber, means for directing the fine spray outward into the current of air as it issues from the walls, means whereby the air current beats downward and inward the coarser particles of water, and means for collecting surplus water.

6. In a humidifier, an outer and an inner wall, an annular air passage between said walls, a spray-chamber within the inner wall, means for supplying air, means for supplying spray to said spray-chamber, means for diverting part of the air inward through the drip from the inner wall, means for directing the remaining air outward and drawing the fine spray with it, and means for collecting surplus water.

7. In a humidifier, an outer and an inner wall, an annular air passage between said walls, a spray-chamber within the inner wall, a drip receptacle below and separated from the inner wall, means for supplying air, means for supplying spray to the spray-chamber, means for directing air across the upper end of said drip receptacle toward the center of the spray-chamber, means for directing air outward and downward across the path of the spray and drawing the spray with it, and means for collecting surplus water.

8. In a humidifier, concentrically arranged air and spray-chambers, a water receptacle below the wall of the spray-chamber, an air passage across and at the

upper end of said receptacle, means for supplying air to the air chamber, means for supplying spray to the spray-chamber, and means for collecting surplus water.

9. In a humidifier, a casing, a spray-chamber, an air chamber between said casing and said spray-chamber, means for collecting water from the wall of the spray-chamber, means for directing air laterally and inward into the spray issuing from the spray-chamber, means for supplying air, means for supplying spray, and means for collecting surplus water.

10. In a humidifier, a casing, a spray-chamber, means for supplying spray, a receptacle to receive water from the wall of the spray-chamber, a vertically adjustable deflector for throttling the spray and supported on the wall of the spray-chamber, means for supplying air, means for directing air inward across said receptacle, and means for collecting surplus water.

11. In a humidifier, a casing, a spray-chamber concentrically arranged in said casing, means for supplying spray, an annular receptacle below and separate from the wall of the spray-chamber and having an outer wall extending above the terminus of the wall of the spray-chamber to direct air inward across said receptacle, a deflector for the spray, means for supplying air, and means for collecting surplus water.

12. In a humidifier, a casing, a spray-chamber concentrically arranged in said casing, means for supplying spray, a receptacle below and separate from the wall of the spray-chamber and having an outer wall extending above the lower end of the wall of the spray-chamber, outlets for water in said wall of said receptacle, a deflector at the discharge end of the spray-chamber, means for supplying air, and means for collecting surplus water.

In testimony whereof I affix my signature, in presence of two witnesses.

STUART W. CRAMER.
